REYNOLD JANNEY, OF NEW YORK, N. Y., ASSIGNOR TO THE WATERBURY TOOL COMPANY, OF NEW BRITAIN, CONNECTICUT, A CORPORATION OF CONNECTICUT.

HYDRAULIC CONTROLLING MECHANISM.

1,131,704.

Specification of Letters Patent. Patented Mar. 16, 1915.

Application filed May 15, 1914. Serial No. 838,716.

To all whom it may concern:

Be it known that I, REYNOLD JANNEY, a citizen of the United States, residing at New York, in the county of New York and State of New York, have invented certain new and useful Improvements in Hydraulic Controlling Mechanisms, of which the following is a specification.

This invention relates to hydraulic controlling mechanism, one of the primary purposes of the invention being the provision of means of an effective character for compensating for changes in space volume of a plurality of hydraulic controlling devices. Hydraulic controlling mechanism involving my invention can be employed with advantage in widely-different connections, although it is of especial utility in connection with an oscillatory member movable oppositely from a central position.

In the drawings accompanying and forming part of the present specification I have shown in detail several of the many different forms of embodiment of the invention which to enable those skilled in the art to practice the same will be set forth fully in the following description. I do not restrict myself to such showing; I may depart therefrom in radical respects within the scope of the invention defined by the claims following said description.

Referring to said drawings: Figure 1 is a sectional top plan view of hydraulic controlling mechanism involving my invention. Fig. 2 is a diagrammatic sectional view. Figs. 3, 4 and 5 are views corresponding to Fig. 1 of different forms of the apparatus.

Like characters refer to like parts throughout the several figures.

My invention comprises a plurality of hydraulic devices connected with a common oscillating member, in conjunction with means for automatically compensating for changes in space volume of said devices. This compensation may be obtained in any desirable manner, best, however, by automatically variably augmenting the liquid

capacity of said devices. In the present instance each hydraulic device consists of a cylinder and a piston within the same, connected by connecting rods with an oscillating member.

Where a piston is connected to a crank by means of a connecting rod or link whose angular position varies relative to the line of movement of the piston, the latter will not move directly in proportion with the angle of the crank movement nor to the sine of the angle of the crank, but will vary with the versed sine of the angle of the connecting rod. If two pistons are connected with two cranks by means of connecting rods and the spaces in the cylinders in advance of the pistons are united by a pipe or pipes and these spaces and pipe or pipes are filled with incompressible fluid, the changes in the obliquity of the connecting rods during oscillations of the cranks, cause changes in the total volume of the spaces in advance of said pistons. I provide means for compensating for these changes in space volume, and as will be inferred this compensation can be secured in many different ways, although satisfactory results are obtained by variably augmenting the capacities of the cylinders or equivalents in correspondence with the degree of movement of the respective cranks from their central positions.

When the hydraulic devices consist of cylinders of equal diameter and pistons within the same, the pistons being connected by rods with an oscillatory member of opposite and equal distances from its center of movement, it is evident that when said oscillatory member is in its central position, the effective space volumes of the opposing cylinders are equal. When, however, the pistons are moved in shifting said oscillatory member from its neutral position then the necessity for the compensating means arises. In the present case the branches of the oscillatory member to which I have alluded constitute cranks. It will be apparent that my invention does not reside in any

specific details but in certain broad relations. These hydraulic devices can be employed for a variety of purposes, for instance for shifting a member when they constitute actuating devices or for checking a part when they act as dash-pots, these being merely two of many uses.

The framing for supporting the different parts of the mechanism may be of any suitable kind; that shown consists of a base or bed 2. There are two cylinders 3 and 4 of duplicate construction, containing pistons 5 and 6 which project beyond the respective cylinders and are pivoted as at 7 and 8 to the connecting rods 9 and 10 respectively, said pivots being carried by similar slides or blocks 11 and 12. The main cylinders 3 and 4 are connected in some suitable manner rigidly with the base or bed 2. From said base or bed rises the support 13 having in its opposite faces ways for guiding the two slides or blocks 11. The rods or links 9 and 10 are pivoted at their outer ends to the branches or arms of the oscillatory member 14 which may constitute the head of a rudder in which event the hydraulic devices will act as actuating devices for said oscillatory member. It will be observed that the rods or links 9 and 10 are connected with said oscillatory member at equal distances from its center of motion.

The space or effective volume of the cylinders 3 and 4 is that provided for the displacement of the pistons. Connecting the forward ends of the two cylinders 3 and 4 is the duct or pipe 16 intersected by a variable reversible pump 17 of ordinary kind and shown conventionally. There are applications wherein a pump is not necessary and a choke or by-pass valve might be used. This pump 17 or its equivalent acts as a convenient device for circulating the liquid from one cylinder to the other and vice versa. The liquid may be of any suitable nature; such as oil, glycerin or water. It will be understood that the space forward of the two pistons 5 and 6 and the duct or pipe 16 is completely filled with the incompressible liquid of whatever nature it may be.

In Fig. 1 the oscillatory member 14 is shown as occupying its central position. It will be supposed that it is necessary to swing the upper branch of the oscillatory member 14 to the right in said view. In this event the pump 17 is thrown into action to pump liquid from the cylinder 3, and force it into the cylinder 4. Should it be desired to oppositely swing the oscillatory member, the reverse action takes place. By reason of the variation in angularity of the connecting rods 9 and 10 during the swing of the oscillatory member 14, a change in space or effective volume of the two cylinders 3 and 4

ensues. I provide various means for compensating for this change, some of which I shall describe.

The compensating means in the organization shown involves auxiliary containing means in communication with the main cylinders 3 and 4 or analogous parts and the cylinder 18 meets my requirement in this particular, although as will be hereinafter set forth, several of such auxiliary cylinders can be employed. This cylinder 18 is fastened in some suitable manner rigidly to the support 13 and is in communication at its forward end with the main cylinders 3 and 4. This communication as will be obvious can be obtained in many ways; as shown the duct or pipe 19 is provided, extending from the forward closed end of said auxiliary or supplemental cylinder to the pipe 16 between the pump 17 and cylinder 4, so that the auxiliary cylinder is in uninterrupted communication with the main cylinders. The space volume of this auxiliary cylinder is automatically varied to compensate for changes in space volume of the main cylinders, and this office can be obtained in various ways, although satisfactory results are secured by operating the piston 20 of said auxiliary cylinder 18 by the oscillatory member 14 in some suitable manner. As shown the oscillatory member 14 is provided approximately at its center with the inwardly extending crank arm 21 furnished with a projecting stud 22 which may consist of an anti-friction roller, disposed within the cam slot 23 formed in the widened outer extended end 24 of the auxiliary piston 20. The cam slot 23 has duplicate portions extending oppositely from a central or ineffective portion which latter the stud 22 occupies when the oscillatory member is in its central position as shown in Fig. 1. The branches of the said slot, however, are so shaped that when the oscillatory member is moved in either direction from its neutral position, the stud 22, on the swing of the crank, acting against the walls of the particular branch in use at such time, will move the piston 20 outward a distance to increase the effective volume of the cylinder 18 an amount exactly equal to the variation in space volume of the cylinders 3 and 4. I will describe more in detail in connection with the diagram in Fig. 2 the exact action in a predetermined movement of the parts.

In Fig. 2 the parts are all shown as occupying their central positions by full lines. In dotted lines the piston 6 is shown as all the way out and the piston 5 as all the way in, this result having been obtained by pumping through the agency of the pump 17 liquid from the cylinder 3 to the cylinders 4 and 18, which resulted in shifting the

oscillatory member from its full line or central position to the dotted line position. The rectangle 25 represents the volume which was displaced when the piston 5 was moved from its full line to its dotted line position. To move the piston 6, however, from the position shown in full lines to that in dotted lines, the maximum outward movement of said piston 6, there should be received in the cylinder 4 a volume of liquid shown by the rectangle 26. It will, therefore, be evident that in moving the oscillatory member from the central position to the dotted line position a volume of liquid should be transferred equal to the rectangle 26, whereas the volume actually taken from the cylinder 3 is represented by the rectangle 25. In this illustration, therefore, there is an excess of liquid which should be disposed of and which is equal to the difference between the pumped volume and the volume received. The pumped volume from the cylinder 3 is represented by the rectangle 25, the received volume into the cylinder 4 being represented by the rectangle 26. The difference is produced by the change in angularity of the connecting rods 9 and 10, each rod producing half the difference, represented by the rectangles 29 and 30 respectively, the sum of these being the total difference. These two volumes represented by said rectangles 29 and 30, may, therefore, be regarded as flowing equally from the two cylinders 3 and 4 by way of the pipe 19 into the auxiliary, or compensating, cylinder 18, the piston 20 of which has been moved back to the dotted line to receive these excess volumes. There is really no flow of liquid from the cylinder 4, but the movement of piston 6 is the resultant of two movements, namely, one due to the logarithmical sine of the angular change of the part 14, and the other due to the change in the angular position of the rod 10. The resultant of these two is their difference, while in the case of piston 5 the resultant is the sum. In the case of both pistons the effects of the rods 9 and 10 are such as to give the pistons positions farther to the left than they would otherwise have, and in this sense the liquid may be regarded as flowing from both cylinders 3 and 4.

Referring now to Fig. 3, the numerals 31 and 32 denote main cylinders and 33 and 34 their pistons, the forward ends of said cylinders being connected by the duct 35 intersected by the pump 36. The rods of the pistons 34 are connected by links or rods 37 and 38 with the duplicate branches of the oscillatory member 39 provided with a crank projection 40 having a cam slot 41 to receive the depending stud 42 on the end of the rod 43 having branches provided with pistons 44 and 45 slidable in the auxiliary cylinders 46

and 47 connected by pipes 48 and 49 with the main cylinders 31 and 32. In the construction shown in Fig. 3 it is very much like that in the preceding views except that I provide two auxiliary or compensating cylinders instead of one. As the oscillatory member 39 is moved in either direction from its central position the effective capacities of the auxiliary cylinders 46 and 49 are increased to compensate for variation in space volume of the two main cylinders 31 and 32.

In Fig. 4 the main cylinders are denoted by 50 and 51, the connection between them being designated by 52 and being intersected by the pump 53. Slidable in the cylinders 50 and 51 are pistons 54 and 55 chambered as at 56 and 57 to present auxiliary cylinders, the chambers or bores 56 and 57 containing the pistons 58 and 59 and being connected by ports 60 and 61 with the front spaces of the main cylinders 50 and 51. The pistons 58 and 59 are shown provided with studs 62 and 63 extending into cam slots 64 and 65 on the inner ends of rods 66 and 67 pivoted at their outer ends to the branches of the oscillatory member 68, the inner portion of the rods or links 66 being pivoted within cavities at the outer ends of the two cylinders 54 and 55. When the oscillatory member 68 is swung in either direction from its central position the pistons 58 and 59 will be moved outward to increase the capacities of the spaces or chambers 56 and 57 to conform to the degree of movement of the said oscillatory member from said central position.

In Fig. 5 the main cylinders are denoted by 70 and 71, the connection between them by 72 and the pump by 73. The cylinders 70 and 71 contain pistons 74 and 75 chambered at 76 and 77 whereby the pistons 74 and 75 in addition to acting as such will also constitute auxiliary cylinders. The chambers or spaces 76 and 77 are connected with the front ends of the cylinders 70 and 71 by ports 78 and 79. The chambers 76 and 77 contain pistons 80 and 81 connected by links 82 and 83 with oppositely disposed cranks 84 and 85 at the forward ends of the rods 86 and 87 pivoted at their outer ends to the branches or arms of the oscillatory member 88. The rods 87 are mounted pivotally in chambers in the outer ends of the pistons 74 and 75 as described in connection with Fig. 4. When the member 88 is moved in either direction from its central position the effective capacities of the chambers 76 and 77 are progressively increased.

As hereinbefore mentioned there are applications of my apparatus wherein the pump is not required, but the pistons are actuated by the turning of the arms 14, 39, 68 or 88, as the case may be. For example the pistons and cylinders might be used as dash

pots to steady or limit the speed of movement of the arms.

What I claim is.

1. The combination of a plurality of hydraulic actuating devices, and means for automatically variably augmenting the liquid capacity of said devices.
2. The combination of a plurality of hydraulic actuating devices, and means for automatically compensating for changes in space volume of said actuating devices.
3. The combination of a plurality of communicating hydraulic actuating devices, an oscillatory member having rods connected thereto, the actuating devices comprising movable members connected with said rods, and means for automatically compensating for changes in space volume of said hydraulic actuating devices.
4. The combination of a plurality of communicating hydraulic devices, pump mechanism for circulating liquid between the hydraulic devices, an oscillatory member, rods connected with said oscillatory member at opposite sides of its axis of motion, the hydraulic devices having movable members connected with the rods, and means for automatically compensating for changes in space volume of said hydraulic devices.
5. The combination of a plurality of hydraulic actuating devices each comprising a movable member, means for circulating liquid between said hydraulic actuating devices, an oscillatory member, rods connected with the oscillatory member at opposite sides of its center of motion and also with said movable members, and means for automatically compensating for changes in space volume of the actuating devices.
6. The combination of a plurality of hydraulic actuating devices, means for positively circulating liquid from one hydraulic actuating device to the other and vice versa, liquid containing means in communication with the said hydraulic actuating devices, and means for automatically changing the capacity of said liquid containing means in accordance with various relations of said hydraulic actuating devices.
7. The combination of a plurality of cylinders, each containing a piston, an oscillatory member having a central position, rods connected with the oscillatory member at opposite sides of its center of motion, and with the piston, means for circulating liquid between the two cylinders, and means for variably augmenting the capacities of the cylinders in correspondence with the degree of movement of said oscillatory member from its central position.
8. The combination of a plurality of cylinders each containing a piston, an oscillatory member having a central position, rods connected with the oscillatory member
9. The combination of a plurality of communicating hydraulic devices each having a movable member adapted to occupy a central position, liquid containing means in communication with the hydraulic devices, and means for automatically progressively increasing the capacity of the liquid containing means as said movable members move from their central positions.
10. The combination of a plurality of cylinders each containing a piston, an oscillatory member having a central position, rods connected with the oscillatory member at opposite sides of its center of motion and with the pistons, means for circulating liquid between the two cylinders, liquid containing means in communication with said cylinders, and means for automatically and progressively increasing the capacity of the liquid containing means as said oscillatory member moves in either direction from its central position.
11. The combination of a plurality of cylinders each containing a piston, an oscillatory member having a central position, rods connected with the oscillatory member at opposite sides of its center of motion and with the pistons, means for circulating liquid between the cylinders, liquid containing means in communication with said cylinders, and mechanism involving cam means, for progressively increasing the capacity of said liquid containing means as the oscillatory member moves from its central position.
12. The combination of a plurality of cylinders each containing a piston, an oscillatory member having a central position, rods connected with the oscillatory member at opposite sides of its center of motion and with the piston, means for circulating liquid between the cylinders, liquid containing means in communication with said cylinder, comprising a piston having a cam slot, the oscillatory member being provided with a crank extension having a stud entering said cam slot whereby on the movement of the oscillatory member from its central position, the capacity of said liquid containing means will be progressively increased.
13. The combination of a plurality of communicating hydraulic devices each having a movable member, liquid containing means in communication with the hydraulic devices, and means for automatically varying the capacity of the liquid containing

means when said movable members move from predetermined positions.

14. The combination of a plurality of communicating hydraulic actuating devices, each having a movable member, an oscillatory member having a central position, rods connected with the oscillatory member at opposite sides of its center of movement and with said movable members, and means 10 for variably augmenting the capacities of the hydraulic actuating devices, in correspondence with the degree of movement of said oscillatory member from its central position.

15. The combination of a plurality of 15 communicating hydraulic actuating devices each having a movable member, and means for automatically variably augmenting the liquid capacity of said devices in correspondence with certain positions of said 20 movable members.

In testimony whereof I affix my signature in presence of two witnesses.

REYNOLD JANNEY.
